LINKWORK

John Hardaker, Woking, Surrey, and Richard Rowland Evans, Barnes, London, England, assignors to Her Britannic Majesty's Principal Secretary of State for the War Department, Whitehall, London, England

Filed Feb. 23, 1962, Ser. No. 175,171
4 Claims. (Cl. 74—586)

This invention relates to linkwork and has for its object to compensate for errors in the transmission of movement therethrough due to different parts thereof being subjected to different and varying temperature conditions such, for example, as may be experienced when one part of the linkwork is located in a casing or container and the other part is arranged exteriorly of such casing or container and is exposed to considerably different temperature conditions. Such variations of temperature conditions normally cause different parts of the linkwork to expand at different rates and this to affect the transmission either in extent or in phase or in both extent and phase.

According to this invention a linkwork having co-acting links that are normally subjected to different and varying temperature conditions has at least one of the links of tubular form which is arranged in a fluid circuit, the temperature of the fluid flowing in the circuit being controlled in accordance with the temperature of the second co-acting link to maintain said co-acting links at substantially the same temperature thereby maintaining a constant relative temperature between said links. The invention may be particularly applied to linkwork connecting the trunnions of a gun and the trunnions of a sighting apparatus mounted on the gun carriage or mounting or upon a vehicle carrying the gun.

The invention is illustrated, by way of example, in the accompanying drawings in which

FIGURE 1 is a diagrammatic view showing the application of the invention to a gun and sighting apparatus carried by an armored vehicle, and

FIGURE 2 is a perspective view of a linkwork diagrammatically illustrated in FIGURE 1.

As shown in the drawings a parallelogram linkage connects the trunnions 1 of a gun 2 mounted in an armored vehicle and the trunnions 3 of a sighting apparatus 4 for the gun which sighting apparatus is located remotely from the gun trunnions. Such linkwork consists of two arms 5, 6, respectively keyed to and extending radially from a gun trunnion or an extension thereof and one of the trunnions upon which the sighting apparatus of the gun is pivotally supported, which arms are connected by a tubular link or rod 7. The ends of the tubular link or rod are sealed, but adjacent the ends thereof are nipples or connectors 8, 9 for insertion into tubing. The fourth side of the parallelogram linkwork is usually formed by part of the body 10 of the vehicle. Secured to or formed integrally with the body of the vehicle, and suitably located, e.g. adjacent the sighting apparatus, is a tank or reservoir 11 for liquid. A pump 12 is also provided. The nipple or connector 8 at one end of the tubular link or rod is connected by tubing 13 to the tank or reservoir and the nipple or connector 9 at the other end of the said tubular link or rod is similarly connected by tubing 14 to the pump 12, the circuit being completed by connecting the pump 12 to the tank or reservoir 11

2

by tubing 15. An expansion chamber 16 or a header tank is associated with the tank or reservoir, which chamber also allows air to be bled from the tank or reservoir so that it can be completely filled with liquid which may be in intimate contact with the body of the vehicle.

5 Liquid is circulated by the pump 12 through the tank or reservoir 11 and the tubular link or rod 7 and the temperature of the liquid is varied in accordance with the temperature of the body of the vehicle due to sunshine, rain or other weather conditions to which it is subjected. By circulation of the liquid the temperature of the tubular link or rod 7 is maintained substantially similar to that of the body of the vehicle and in consequence the distance between the trunnions of the gun and the sighting apparatus and the length of the tubular link or rod will be maintained substantially equal.

10 In cases where all the links of a linkwork consist of rods, these may all be tubular and so connected together that liquid can be circulated through all of the said links or tubes. With such a construction of linkwork the provision of a liquid reservoir or tank may not be necessary.

We claim:

1. A linkwork comprising co-acting links that are 25 normally subjected to different and varying temperature conditions, at least one of said links being solid in cross section and at least one of said links being tubular in cross section, a reservoir vessel located in the same ambient environment as a link solid in cross section so that 30 the temperature of the vessel is in substantial equilibrium with that of said link solid in cross section, pump means, and conduit means connecting said vessel, tubular link and pump to form a closed circuit for the flow of fluid therethrough.

35 2. A linkwork comprising a tubular link and a co-acting link which are normally subjected to different and varying temperature conditions, reservoir means subjected to substantially the same temperature conditions as said co-acting link, conduit means interconnecting said reservoir means and said tubular link, and means to circulate fluid in a closed circuit from said reservoir means through said tubular link to maintain said links at substantially the same temperature.

3. A linkwork according to claim 2 wherein said means 45 to circulate fluid comprises a pump.

4. A linkwork including a fixed link, a tubular link disposed parallel thereto and spaced therefrom by connecting arms disposed adjacent each end of said tubular link, reservoir means disposed to be subjected to substantially the same temperature conditions as said fixed link, first conduit means interconnecting said reservoir means and one end of said tubular link, second conduit means interconnecting the other end of said tubular link and said reservoir means, and pump means to circulate fluid in a closed circuit from said reservoir through said tubular link to maintain said links at substantially the same temperature.
